UNITED STATES PATENT OFFICE

HAROLD A. DAVIS, OF CHICAGO, ILLINOIS, ASSIGNOR TO GENERAL CHEMICAL COMPANY, OF NEW YORK, N. Y., A CORPORATION OF NEW YORK

CONVEYER OPERATED SCREENING DEVICE

Application filed May 17, 1929. Serial No. 363,917.

This invention is concerned with apparatus for conveying and separating mixtures of solid constituents which are in different degrees of fineness or sub-division. Its chief object is to provide an automatic screening apparatus for sifting out the smaller particles from admixture in a continuously moving stream consisting of these and larger particles, such as the output mixture from a salt cake furnace, a pulp drier, or the like.

Another object of the invention is to provide conveying and separating apparatus of such nature that no driving or operating mechanism other than that provided by the conveyer itself is required to operate the separator.

A particular object of the invention is to provide a screening device which will have but a few parts of an extremely simple, inexpensive construction, and which will be unlikely to become clogged or jammed with the material or otherwise get out of order.

The preferred embodiment of the inventive idea is shown in the accompanying drawings, wherein

Fig. 1 is a perspective view of the apparatus;

Fig. 2 is a longitudinal section thereof on line 2—2 of Fig. 1; and

Fig. 3 is a plan view of the apparatus.

Referring now to the structure illustrated, the apparatus comprises a chute made up in the usual manner into a hollow, more or less rectangular trough 1 having as desired an open or a closed top, and a bottom 1' closed except at the place where the separation and delivery of one of the constituents of the mixture is desired. At this place there is a rectangular opening 2 in the bottom of the trough, and extending transversely across the center of this opening a shaft 3 is journaled freely in straps 4 attached to the bottom flanges on the side-girders of the trough.

The screen 5, preferably in the form of a perforated plate of sheet metal, is mounted in the opening 2 on shaft 3, the shaft supporting the screen substantially on its transverse median line.

The screen is free to rock or oscillate about the shaft as a pivot from one side to the other.

To limit the extent of the upward and downward movement of the ends of the screen, transversely extending stops 6 are provided at each end of the opening below the bottom level of the trough, and are connected thereto by suitable angle irons or the like 7.

The plate constituting screen 5 is perforated with oval holes 9, the axes of the ovals preferably being parallel to each other and to the direction of movement of the material. These ovals are of the proper size and shape to permit the passage of relatively fine material, but not large enough to let the larger pieces or cakes fall through or hinder their passage over the screen.

On the longitudinal center-line of the plate, situated at equal distances from the transverse center-line of the shaft, are two lugs or cams 10, preferably of rectangular shape as shown in Fig. 3, and both chamfered or rounded off on their forward edges 11, as shown. These lugs are welded or otherwise firmly attached to the plate.

An endless conveyer 12 moves over the bottom of the trough for the purpose of pushing or dragging the mixture of solid materials along the same. The conveyer shown consists of a pair of chains 13 having heavy bars or pushers 14 mounted between them at suitable intervals. The pushers 14 engage the lugs or cams 10 on the screen which causes the screen to be rocked or oscillated about the shaft 3 on which it is mounted.

By making the longitudinal spacing of the lugs 10 only slightly smaller than the spacing or pitch of the pushers 14, the second or rear lug 10 is engaged by one of the pushers 14 very quickly after the forward lug 10 has been engaged by the preceding pusher 14. In this way a relatively rapid rocking or vibration of the screen is produced.

It will be understood that the rapid vibration of the screen produced in the manner just described causes the finer particles of the solid material moving over the screen to pass through the interstices or perforations into the hopper or bin 15. The coarser particles which are too large to pass through the screen move on along the trough under the action of the conveyer, and are carried to a point of

further treatment or to storage, as desired.

The perforated plate comprising the screen 5 is bent downwardly at each end as indicated at 8 of Fig. 2 to form feet to engage the stops 6 and to facilitate the movement of the material in the trough or chute on to and off of the screen. Moreover, it will be noted that the outer ends of the feet 8 are close to the inner walls of the angles 7 so as to leave just enough clearance to permit the plate to vibrate freely. Thus it is impossible for large particles of the solid material passing over the screen to become lodged in this space and cause jamming of the screen.

The movement of each end of the screen away from the stops 6 is however sufficient to permit any relatively fine material which may have entered the space at the ends of the screen to pass horizontally over the stops 6 and mix with the material which has passed through the screen.

The elevation of shaft 3 upon which the screen is supported is preferably such as to bring the top of the screen slightly below the upper surface of the bottom of the trough when the screen is in mid-position. Also the clearance between the bottoms of the feet 8 and the stops 6 is such as to cause the upper surfaces of the ends of the screen to be raised slightly above the bottom of the trough when the opposite end of the screen is in engagement with one of the stops 6. This facilitates the passage of the coarse material off from the rear end of the screen on to the bottom of the trough because during a part of the cycle of vibration the rear end of the screen is raised above the bottom of the trough. This, moreover, enables the solids to pass on to the front end of the screen without difficulty because during a portion of the cycle of vibration the front end of the screen is below the bottom of the trough. The rounded surfaces of the ends of the screen also aid in allowing the solids to pass over the vibrating screen without difficulty.

The conveyer shown is of the "drag" or "pusher" type, but any other type of conveyer having spaced elements preferably extending transversely of the trough to engage the lugs 10 might be used. Also in the conveyer shown the pusher bars 14 are mounted with the bars at right angles to the chain but while this construction is preferable, it is not necessary as far as the operation of the vibrating screen is concerned and the bars could be otherwise mounted as, for example, at a diagonal to the chain.

In operation my improved screening device is extremely satisfactory because of freedom from clogging, and because of the effectiveness with which the fine material is separated from the coarser material. The rapid vibration imparted to the screen shakes the finer particles free from the coarser ones and the fines pass down through the perfora-

tions of the screen without difficulty. Moreover the screen operates in such a way that the material passes over it without increasing the drag on the conveyer to any great extent. The particular mounting of the screen and construction of the ends of the screen prevent the coarse material from becoming jammed between the stationary and moving parts in such a way as to prevent the vibration of the screen.

An important advantage of the improved screening device is that it can be installed without difficulty at any convenient point in the conveyer inasmuch as it requires for its operation no separate drive mechanism. All that is necessary is to make an opening at the desired point in the conveyer trough, surround it with suitable steel shapes to protect the edges of the trough and to form the stationary parts and mounting for the screen.

A further advantage of the screening device is its low cost of manufacture and installation which proceeds from its simplicity and small number of parts.

It will be understood that the foregoing description of the preferred embodiments of my invention is to be considered as an exemplifying disclosure and that the invention extends to other embodiments which are included within the terms of the appended claims.

I claim:

1. A conveyer system comprising a conveyer, a conveyer chute therefor having an opening in the bottom thereof, a screen pivotally mounted in said opening, and co-acting means on the conveyer and on the screen for oscillating said screen by the passage of the conveyer thereover.

2. In a conveyer system including a conveyer and a trough therefor having an opening therein, a screening device for separating constituents of the material conveyed comprising a shaft extending transversely of said opening and supported at the sides thereof, a screen mounted thereon for permitting only the finer particles of the material to fall through said opening, actuating means associated with the screen, and means on said conveyer for engaging said actuating means during the travel of the conveyer and causing the rocking of the screen about its supporting shaft.

3. In a conveyer system including a conveyer and a trough therefor having an opening therein, a screen, means for supporting the screen substantially at its transverse median line in the opening in the trough, a transverse stop member at each end of the opening for limiting the vertical movement of each end of the screen, the screen having downwardly curved ends terminating in feet for engaging the stop members, means for causing the screen to vibrate vertically on its pivotal support, and vertical walls at each

end of the opening in the trough connecting the upper surface of the bottom of the trough with the transverse stop members, and located in close proximity to the downwardly curved ends of the screen so as to prevent the passage of large particles of material, but freely passing relatively small particles without causing jamming of the screen.

4. In a conveyer system including a conveyer and a trough therefor having an opening therein, a screen mounted in said opening on centrally located pivots to permit vibration of the screen, means for causing the screen to vibrate, and stops for limiting the vertical movement of each end of the screen positioned to permit each end of the screen to rise above the bottom surface of the trough during a portion of the cycle of vibration.

5. In a conveyer system including a conveyer and a trough therefor having an opening therein, a screen mounted in said opening on centrally located pivots to permit vibration of the screen, means for causing the screen to vibrate, said pivots being disposed so as to support the upper surface of the screen at an elevation slightly below the upper surface of the trough when the screen is in the mid-position of its cycle of vibration, and stops at each end of the screen positioned to permit each end of the screen to rise slightly above the bottom surface of the trough during a portion of the cycle of vibration.

6. In a conveyer system including a conveyer and a trough therefor having an opening therein, a screen mounted in said opening on centrally located pivots to permit vibration of the screen, means for causing the screen to vibrate, stops for limiting the vertical movement of each end of the screen positioned to permit only a limited amplitude of vibration and to permit each end of the screen to rise above the bottom surface of the trough during a portion of the cycle of vibration, and the screen being provided with downwardly curved end portions, said limited vibration and said curved end portions serving to facilitate the reception and discharge of solid material from respectively the front and rear ends of the screen.

7. In a conveyer system including a conveyer and a trough therefor having an opening therein, a screen pivotally mounted in the opening for vertical vibration about its transverse median line, a pair of lugs projecting upwardly from the screen, one of said lugs being on each side of the transverse center line of the screen, said lugs being substantially equi-distant from said center line, and the conveyer having spaced transverse bars adapted to engage said lugs during the travel of the conveyer and cause the vibration of the screen.

8. In a conveyer system including a con-

veyer and a trough therefor having an opening therein, a screen pivotally mounted in the opening for vertical vibration about its transverse median line, a pair of lugs projecting upwardly from the screen one on each side of the transverse median line thereof, said lugs being substantially equi-distant from said median line, the conveyer having spaced transverse bars adapted to engage said lugs during the travel of the conveyer and cause the vibration of the screen, the spacing of said lugs being such that the first lug is engaged by a transverse bar of the conveyer to depress the front portion of the screen and thereafter the second of said lugs is engaged by the preceding transverse bar to depress the rear portion of the screen.

9. In combination, a conveyer, a screen mounted beneath the conveyer, and means on the conveyer coacting with means on the screen for moving the screen on movement of the conveyer.

10. In combination, a conveyer, a vertically oscillatable screen mounted beneath the conveyer, and means on the conveyer coacting with means on the screen for oscillating the screen on movement of the conveyer.

11. In combination, a conveyer, a screen mounted beneath the conveyer, screen actuating means on the conveyer, a member positioned to engage the actuating means and connected to the screen for moving the screen on movement of the conveyer.

12. In combination, a conveyer, a vertically oscillatable screen mounted beneath the conveyer, screen actuating means on the conveyer, a member positioned to engage the actuating means and connected to the screen for oscillating the screen on movement of the conveyer.

13. In a conveyer system including a conveyer and a trough having an opening therein, a screen mounted in the opening, screen actuating means on the conveyer, a member positioned to engage the actuating means and connected to the screen for moving the screen on movement of the conveyer.

14. In a conveyer system including a conveyer and a trough having an opening therein, a vertically oscillatable screen mounted in the opening, screen actuating means on the conveyer, a member positioned to engage the actuating means and connected to the screen for oscillating the screen on movement of the conveyer.

In testimony whereof, I affix my signature.
HAROLD A. DAVIS.
